UNITED STATES PATENT OFFICE.

FRANCIS X. DEVLIN, OF CHICAGO, ILLINOIS.

OIL-CUP.

1,311,327.

Specification of Letters Patent. Patented July 29, 1919.

Application filed January 14, 1918. Serial No. 211,765.

To all whom it may concern:

Be it known that I, FRANCIS X. DEVLIN, a citizen of the United States, residing at Chicago, in the county of Cook and State 5 of Illinois, have invented certain new and useful Improvements in Oil-Cups, of which the following is a specification.

My invention relates to oil cups and has for its primary object the provision of an 10 improved construction whereby the cap closing spring is protected from the accumulation of dirt and positioned for immersion in fresh oil at each filling of the cup. Another object is to provide an improved construction for holding the cap of the oil cup 15 open against the force of the closing spring. As a further object the parts are so arranged as to permit unobstructed access to the main oil-holding chamber of the cup for purposes 20 of cleaning and filling.

Other objects and advantages of the invention will appear from the following description taken in conjunction with the accompanying drawings, wherein:

25 Figure 1 is a top plan view of the invention with the cap closed; Fig. 2 is a similar view with the cap opened; Fig. 3 is a section approximately on line 3-3 of Fig. 1; Fig. 4 is a side elevation with the cover 30 opened and a portion sectioned approximately on line 4-4 of Fig. 2; Fig. 5 is a rear elevation of the invention with the cap closed; Fig. 6 is a fragmentary detail view 35 illustrating the arrangement whereby the cap and the oil cup are wedged together in position, the spiral divergence of the wall of the oil cup with respect to the cap pivot being exaggerated.

Reference numeral 10 indicates generally 40 the preferably vertical wall of a tubular oil cup, which is reduced at its lower end, as at 11, in order that it may conveniently fit within the aperture provided in a bearing. Reference numeral 12 in Figs. 2 and 3 indicates generally the main oil holding chamber 45 of the oil cup.

At its upper portion the wall 10 of the oil cup is laterally extended to form an oil holding recess 13, having a rear wall 14 and 50 parallel side walls 15 and 16, these walls of the recess being continued to the upper end of the tube so that they lie flush with and form a part of the upper horizontal edge 17 of the oil cup. The recess 13 has unob- 55 structed communication, and preferably

throughout its length, with the main chamber 12 and is so formed that it drains from its bottom extremity into that chamber. A horizontal pivot shaft 18 is fixed near its ends in the walls 15 and 16 of the recess, 60 the main body of the shaft lying within the recess and below the upper edge thereof, and the extreme ends of the shaft projecting respectively from the walls 15 and 16 for engagement with lugs 19 and 21 which depend from a cap 22, shaped to cover the chamber and the recess. Coiled about the shaft 18 is a cap closing spring 23, the end 24 of which is fixed to the cap 22 and the other end 25 of which is fixedly connected to 70 the wall of the recess 13. If desired, the end 25 of this spring may be attached to the pivot shaft 18 inasmuch as that shaft is preferably brazed into the walls 15 and 16 to prevent leakage of oil. In attaching 75 the end 24 to the cap, I prefer to drill the cap with a hole into which the end of the spring closely fits and then braze or solder the end to the cap.

The upper end 26 of the rear wall 14 of 80 the recess is flat as regards horizontal extension, but is curved so that, as shown in Figs. 3 and 4, it diverges from the axis of the shaft 18. As illustrated, this divergence of the wall 26 is in the direction of the opening movement of the cap 22. At its rear 85 end the cap is curved downwardly to form a tail 27 which externally overlaps the wall 26 and has its edge 28 positioned so close to wall 26 as to cause the tail to wipe against 90 and finally wedge frictionally upon the wall 26 when the cap is fully opened.

In using this oil cup, and considering the cup closed as in Fig. 3, the operator opens the cap into the substantially vertical position illustrated in Fig. 4. By reason of the gradually diverging relation of the portion 95 26 of the rear wall with respect to shaft 18, the tail 27 of the cap will wedge against wall 26 with sufficient friction to overcome 100 the closing force of the spring 23, thereby maintaining the cap in the open position shown in Figs. 2 and 4. The operator now fills the oil cup immersing both the shaft 18 and all of the spring 23, except the end 24. He now closes cap 22, as illustrated in Figs. 1, 3 and 5, whereupon the force of the spring 23 holds the cap closed. If the cup has been 105 filled to the upper edge 17 this closing of the cap will immerse in the oil every portion of 110

the spring 23, except the tips thereof, which are brazed into the cap and wall.

It is an advantage of the present invention that the spring 23 receives a fresh bath of oil in each filling of the cup, this occurring by reason of the fact that the recess 13 forms a portion of the oil feeding chamber, and as the oil in the cup flows out into the bearing all the oil in the recess drains off also into the bearing and is used. The spring therefore is not immersed in a body of oil that remains stationary in a separate recess to dry out and gum the spring, but is lubricated with the same frequency as the bearing itself. When considered in connection with the other advantage of having the spring inclosed from the air and dust and dirt carried thereby, it will be seen that my improved construction tends to prolong the life of the spring and to cause it to work easily at all times.

A further advantage of my improved arrangement is best illustrated in Fig. 2, wherein it will be seen that when the cap 22 stands in open position, the cap, pivot shaft and spring are all laterally clear of the main bore 12 of the oil cup. The result of this arrangement is that the cleaning and filling of the cup are facilitated by removal of all obstacles to direct access.

It is contemplated that in the manufacture of this invention, the body portion of the cup will be formed from a tube originally of the diameter of the reduced portion 11 and that the portion 10 of the cup will be spun out in the well known manner. The walls of the recess 13 may be readily forced out by a die from the wall of the portion 10. The cap 22 is a plain sheet metal punching bent to form the lugs 19 and 21 and the tail 27. The lateral edge of the tail 27 may be brazed to the rear edge portions of the lugs as illustrated in the drawings or, if it be desired to provide a greater degree of resiliency in the tail of the cap this brazing may be omitted. Cheapness of construction and ease of manufacture are therefore further advantages of my invention.

I claim:

- 50 1. The combination with an oil cup, of a cap therefor pivoted to the cup on a horizontal axis, and a cap closing spring mounted in the oil-feeding cavity of the cup clear of the main bore thereof.
- 55 2. The combination with an oil cup, of a horizontal shaft fixed near its ends in the wall thereof and traversing the oil-feeding cavity of the cup, a cap pivoted on the shaft, and a cap closing spring coiled about the shaft and lying within said oil-feeding cavity.
- 60 3. The combination with an oil cup, of a horizontal shaft fixed near its ends in the wall thereof and traversing the oil-feeding cavity of the cup, a cap pivoted on the shaft,
- 65

and a cap closing spring coiled about the shaft and lying within said oil-feeding cavity; the ends of said spring being respectively connected to said cup and cap.

4. The combination with an oil cup the wall of which is extended laterally to form an oil-holding recess draining at its bottom into the main oil cavity of the cup, of a cap for the cup and recess pivotally supported on the wall of said recess, and a cap closing spring positioned within the recess below the upper edge thereof and having its ends respectively connected to the cup and cap.

5. The combination with an oil cup, of a cap pivoted thereto, the cap and the wall of the cup being shaped to wedge together when the cap is in open position.

6. The combination with an oil cup, of a cap pivoted thereto on a given axis, a portion of the wall of the cup being formed eccentrically with respect to said axis and the cap being shaped to wedge against said portion of the wall in its opening movement.

7. The combination with an oil cup, of a cap pivoted thereto on a given axis, a portion of the wall of the cup diverging from said axis, and the cap being shaped to wedge against said diverging portion of the wall in its opening movement.

8. The combination with an oil cup, of a cap pivoted thereto on a given axis, a portion of the wall of the cup diverging eccentrically from said axis in the direction of the opening movement of the cap, and a tail on the cap exteriorly overlapping the diverging portion of the wall and positioned to wipe against the same during said opening movement.

9. The combination with an oil cup the wall of which is extended laterally to form an oil-holding recess, of a cap for the cup and recess pivoted to the cup on an axis which traverses the recess, one wall of said recess paralleling said axis and diverging eccentrically therefrom in the direction of the opening movement of the cap, and the cap being shaped to overlie the diverging portion of the recess wall and to wipe against the same during said opening movement.

10. The combination with an oil cup, of a cap pivoted thereto on a given axis, a portion of the wall of the cup being curved eccentrically with respect to said axis and intervening between the cap and its axis.

11. The combination with an oil cup having a main tubular oil-holding chamber and a lateral oil-holding recess the bottom of which drains into said chamber, of a pivot-shaft traversing the recess and bearing in the wall thereof, a cap for the cup and recess pivoted on said shaft, and a cap closing spring coiled about the shaft and having its ends respectively connected to the cup and cap; the cap, shaft and spring

115

130

standing laterally clear of the main bore of said chamber during the open position of the cap.

12. The combination of an oil cup having 5 a main tubular oil-holding chamber and a lateral oil-holding recess the bottom of which drains into said chamber, of a pivot shaft traversing the recess and bearing in the walls thereof, a cap for the cup and recess pivoted on said shaft, and a cap clos-

ing spring coiled about the shaft and having its ends respectively connected to the cup and cap; the cap, shaft and spring standing laterally clear of the main bore of said chamber during the open position of 15 the cap; the wall of the recess and said cap being shaped to wedge together when the cap is in open position.

FRANCIS X. DEVLIN.
